UNITED STATES PATENT OFFICE.

JACK R. GOLDEN, OF CLEVELAND, OHIO.

DESIGN FOR A TEETHING APPARATUS.

47,419.

Specification for Design.

Patented June 8, 1915.

Application filed March 15, 1915. Serial No. 14,612. Term of patent 14 years.

To all whom it may concern:

Be it known that I, JACK R. GOLDEN, a citizen of the United States, residing at Cleveland, in the county of Cuyahoga and State of Ohio, have invented a new, original, and ornamental Design for a Teething Apparatus, of which the following is a specification, reference being had to the accompanying drawing, forming part thereof.

Figure 1 is a face view of a teething appa-

ratus embodying my design. Fig. 2 is an edge view thereof.

I claim:

The ornamental design for a teething apparatus, as shown.
